(57) **CLAIM**

The ornamental design for a wireless mouse, as shown and described.

DESCRIPTION

FIG. 1 is a front, left and bottom perspective view of a wireless mouse, showing our design.

FIG. 2 is a rear, right and top perspective view thereof.

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

FIG. 9 is an enlarged view of portion 9 shown in FIG. 1; FIG. 10 is an enlarged view of portion 10 shown in FIG. 2; and,

FIG. 11 is a front, left and bottom perspective view showing the wireless mouse with the cover removed for completeness of illustration.

The dashed-dot-dashed lines depict the exact locations of the cross sections of the wireless mouse. The broken lines represent structures that for no part of the claimed design.
